UNITED STATES PATENT OFFICE.

UTLEY WEDGE, OF ARDMORE, PENNSYLVANIA.

METALLURGICAL FURNACE.

1,208,249.

Specification of Letters Patent. Patented Dec. 12, 1916.

Application filed November 21, 1914, Serial No. 873,246. Renewed April 27, 1916. Serial No. 94,055.

To all whom it may concern:

Be it known that I, UTLEY WEDGE, a citizen of the United States, residing in Ardmore, Pennsylvania, have invented certain improvements in Metallurgical Furnaces, of which the following is a specification.

The object of my invention is to supply air to the different chambers of a roasting furnace in such manner that said furnace will be caused to work at its maximum efficiency for sulfur elimination or other oxidizing work. This object I attain in the manner hereinafter set forth, reference being had to the accompanying drawings, in which—

Figure 1 is a vertical sectional view of a superposed-hearth furnace having four hearths and equipped with a simple form of air supplying device in accordance with my invention, the usual rabble arms being omitted; Fig. 2 is a sectional plan view on the line *a—a*, Fig. 1; Figs. 3, 4, 5 and 6 are face views, on an enlarged scale, of the different controlling valves in their relation to the air conveying pipes; Fig. 7 is a vertical sectional view of a furnace having another form of valve control for the air supply; Figs. 8, 9, 10 and 11 are, respectively, sectional plan views on the lines *b—b*, *c—c*, *d—d*, and *e—e*, Fig. 7; Fig. 12 is a vertical sectional view illustrating one method of applying my invention to a furnace in which the air supply is heated by means of the rabble arms, and Figs. 13, 14, 15 and 16 are sectional views illustrating the simplest means for controlling the air.

In order to operate a roasting furnace at its maximum efficiency for sulfur elimination or other oxidizing work the amount of air admitted to each of the progressive hearths of the furnace should be varied, being gradually reduced as the pyrites or other material which is being roasted passes from hearth to hearth of the furnace, for instance, in a four hearth furnace such as that shown in the drawing the percentage of total air entering the furnace may be distributed as follows: To the top hearth 40%, to the second hearth 30%, to the third hearth 20%, and to the bottom hearth 10%, or in a furnace in which air is supplied to six hearths the percentage of the total air entering the furnace may be distributed as follows: 25% to the first hearth, 25% to the second hearth, 20% to the third hearth, 15% to the fourth hearth, 10% to the fifth hearth, and 5% to

the sixth hearth, or the respective percentages may be varied so long as there is a progressive diminution in the volume of air supplied to the mass of material passing through the furnace.

Fig. 1 of the accompanying drawings represents a superposed hearth furnace of the type heretofore patented by me but provided with means in accordance with the present invention for supplying graduated volumes of air to the different chambers of the furnace. The furnace shown in the drawings has four hearths 1, 2, 3 and 4 disposed one above another, but it may have any desired number of hearths, depending upon the character of the furnace and the purpose for which it is to be used.

The furnace has a central rotating shaft 5 which is intended to carry the usual rabble arms and rabbles whereby the stirring and feeding of the material on the hearths of the furnace is effected, these rabble arms and rabbles, however, not being shown in Fig. 1 as their illustration is not necessary to a proper understanding of my present invention.

The shaft 5 has, at its lower end, a suitably mounted gear wheel whereby it can be rotated and the hub of this gear wheel forms a water-sealed or other air tight joint with a casing 6, which is supplied with air by means of an injector 7 or other suitable device, this air passing up through the hub of the gear wheel and into a pipe 8 centrally disposed within the shaft 5 and having hollow arms 9 extending therefrom into different chambers of the furnace, these arms communicating at their inner ends with the interior of the pipe 8 and each discharging at its outer end into the chamber with which it communicates.

The admission of air to the hollow arms 9 is controlled by suitable vertically sliding valves 9^a which determine the effective inlet area of each arm, as shown in Figs. 3, 4, 5 and 6, consequently, assuming that air under pressure is admitted to the pipe 8, such air may be discharged in graduated volumes into the different chambers of the furnace. The valves 9^a have operating rods 9^b projecting above the pipe 8, so as to be operated from the outside of the furnace.

In the structure shown in Figs. 7 to 11, inclusive, the admission of air to the various arms 9 is controlled by rotary valves 10 adapted to seats on the inner face of the

2
pipe 8 and having independent stems 11 which project above the top of the shaft 5 and are provided with handles 12 whereby any one of the valves 10 may be conveniently and independently turned so as to open, close or adjust the same, and thereby regulate the flow of air through the arms 9, as may be desired, for the effective operation of the furnace.

10 In some furnaces the air which is supplied to the different chambers to effect oxidation of sulfur elimination is first heated, a common method of thus preheating the air being to pass it through the rabble arms 5 of the furnace, and in Fig. 12 I have illustrated the application of my invention to a furnace of this type. The air passes from the central pipe 8 through a pipe 13 into the inlet chamber of the rabble arm 14 and discharges from the outlet passage of said arm into the shaft 5, and from the interior of the latter passes through the arms 9 into the various chambers of the furnace, the arms being suitably valved as at 9^a to regulate 20 the volume of air admitted to each chamber. This construction may, however, operate reversely if desired, that is to say, the air may be admitted in the first instance to the hollow shaft 5, may be passed thence to the 25 conducting passages of the rabble arms and may be delivered by the latter into the central pipe 8 from which it is distributed to the various chambers of the furnace.

In Figs. 13 to 16 I have shown a means 30 of regulating the volume of air supply by applying to the inner ends of the arms 9 plugs or bushings 15 and providing each of these plugs with an opening of appropriate diameter.

40 Although I have shown my invention as applied to the ordinary "Wedge" type of furnace having a series of superposed chambers, it will be evident that it can be applied to a furnace having the chambers otherwise

disposed, or to a furnace having but a single chamber if desired, the air being admitted to this single chamber at different points and the volume of air admitted at any one point being proportionate to the requirements of the material under treatment at 50 that particular point in its progress through the chamber.

I claim:

1. The combination, in a metallurgical furnace, of a casing having a hearth with a 55 treating chamber above the same, a shaft, an arm projecting therefrom into said treating chamber and open at its shaft end, a valve sliding across said open end of the arm but otherwise rigidly mounted, and 60 means for imparting such sliding movement to said valve, said means being otherwise rigid.

2. The combination, in a metallurgical furnace, of a casing having a hearth with 65 treating chamber above the same, a tubular shaft having a tubular member within the same, a hollow rabble arm having a return passage therein which communicates at one end with the interior of the tubular shaft 70 and at the other end with the interior of the tubular member within the shaft, an air distributing arm projecting into the working chamber of the furnace but independent of the rabble arm, said air distributing arm communicating with but one 75 of said tubular members, means for supplying air to the other of said tubular members, and means for regulating the flow of said air from the air distributing arm into 80 working chamber of the furnace.

In testimony whereof, I have signed my name to this specification, in the presence of two subscribing witnesses.

UTLEY WEDGE.
